MEDICAL SUCTION VALVE

Marvin Katzman, 1520 202nd St., Bayside, N.Y. 11368,
and Neil De Fluri, 952 Arnet Ave., Union, N.J. 07083

Filed Oct. 3, 1973, Ser. No. 463,632

Term of patent 14 years

Int. Cl. D24—02

U.S. Cl. D32—1 R

FIG. 1

FIG. 2

FIG. 3

FIG. 4

FIG. 5

FIG. 1 is a perspective view of a medical suction valve showing the new design in the open position.

FIG. 2 is another perspective view thereof, shown in the closed position.

FIG. 3 is a front elevational view of FIG. 1.

FIG. 4 is a left end elevational view of FIG. 1.

FIG. 5 is a right end elevational view of FIG. 1.

We claim:

The ornamental design for a medical suction valve, as shown and described.
